(57) **CLAIM**

We claim the ornamental design for a light-up aquarium, as shown and described.

DESCRIPTION

FIG. 1 is a perspective view of the light-up aquarium.

FIG. 2 is a side view of the light-up aquarium.

FIG. 3 is a top view of the light-up aquarium; and,

FIG. 4 is a bottom view of the light-up aquarium.

The broken lines in the drawings define boundary lines and form no part of the claimed design.

The left side, right side, front, and rear views are identical to the side view shown.
